OF PARIS, FRANCE.

TELESCOPIC MAST.

1,221,723.

Specification of Letters Patent.

Patented Apr. 3, 1917.

Application filed October 7, 1911. Serial No. 653,406.

To all whom it may concern:

Be it known that I, MARCEL GUICHARD, of 7 Rue Duranti, in the city of Paris, Republic of France, engineer, have invented a 5 Telescopic Mast, of which the following is a full, clear, and exact description.

The invention has for its object a telescopic mast or post support applicable in all the cases where it is desired to produce or 10 receive electric actions. The apparatus may serve particularly for wireless telegraphy or telephony, for the reception of electric atmospheric actions and for all applications of the same kind.

15 The existing telescopic post-supports may be classified in two categories.

To the first category belong the supports which are previously extended on the ground and set upright afterward.

20 The tubes which form these supports must be very strong and are consequently rather heavy.

In the second category, the supports are erected vertically, and the tubes need not 25 be as strong as those of the first category.

The support forming the subject-matter of this invention belongs to the second category, but does not comprise any lifting device proper as heretofore employed and its 30 total weight is very slightly superior to that of the tubes. Therefore it presents an important reduction of weight comparatively to all existing supports.

Besides, the support when extended has 35 more rigidity than an ordinary support of equal size and possesses a longitudinal elasticity imparting to the same exceptional qualities as will be specified in detail hereafter.

The new support is substantially characterized by this fact that its elements form 40 a fluid-tight capacity of variable volume, in which is sent, when erecting the support, a fluid under pressure.

By way of example, one method of putting the invention into practice will be described.

In this method each tube forms a tight joint with the tube in which it slides, so 45 that the whole of these tubes forms a tight 50 extensible system in which can be sent the fluid under pressure.

This arrangement is illustrated by way

of example only in the accompanying drawings, in which:

Figure 1 is a section of the extended support; 55

Fig. 2 is a section showing the support folded;

Fig. 3 is a detail view on an enlarged scale. 60

As shown in the drawings, the support comprises tubes a , a^1 , a^2 , the number of which may vary, sliding in one another.

The joint between two tubes is formed as shown in Fig. 3; at the bottom of a tube a^1 65 are secured two rings b and c ; the outer diameter of the ring b is slightly less than the inner diameter of the tube a for allowing an easy sliding movement.

The tube a carries at its upper part a 70 collar d provided with a ledge e leaving internally a certain play between said ledge and the tube a^1 .

Between the tubes a and a^1 is arranged a short section of tube f which, when erecting 75 the support, abuts against the ring b and the ledge e , as illustrated in Fig. 3, this limiting the relative stroke of the tubes a , a^1 , etc.

In the washer c are fixed two chased 80 pieces of leather g and h which are secured by washers i and j tightened by a bolt and a nut.

The washers i and j are provided with orifices k and l to allow of communication between the tubes. 85

The lower tube is closed at its lower end and the upper tube at its upper end. The lower tube is provided at its lower end with a point adapted to enter the ground. 90

A valve or flap valve m allows the introduction of the fluid under pressure.

The support is erected as follows:

The tubes being in the position shown in Fig. 2, placed vertically, the valve m is 95 connected to an air compression pump or to a compressed air tank. Under the action of the pressure, the elements emerge from one another up to complete or partial development at will.

100 Stays n , in any suitable number, which may be formed by the post itself, hold the support in its vertical position during and after its erection.

It suffices to open the valve *m* for obtaining the descent of the tubes and the folding of the support.

Instead of using air for erecting the support, any compressed gases may be used, for instance liquefied gases; these gases can be contained in a small vessel, situated within the support and opened when the support is to be erected.

10 In addition to its light weight, the facility of its erection and its adjustable rigidity resulting from the inner pressure, the new support possesses special important advantages due to its longitudinal elasticity.

15 1. It frequently happens during the erection of the mast or post or even after the same has been erected, that the stay wires or ropes forming part of said post become mixed together under the influence of the

20 wind or from any other cause; besides, one of said wires or ropes may be broken or it may be necessary to wipe up the rain water or remove frost that may cover the insulators on the mast or post.

25 In all these cases, it is necessary to bring down the post and its support in order to have access to the posts to be inspected. In all existing post supports it is necessary to put in action for the descent erection devices 30 which are more or less complicated and the operation of which requires a long time. The support forming the subject matter of this invention allows of bringing down the post and its support to any required extent 35 by a simple traction exerted longitudinally to the support by means of the post wires or ropes, of the stays or any other ropes connected to the mast.

2. The traction which it is possible to exert on the support in the longitudinal direction moreover allows the tubes to reenter in one another entirely or partially without causing the escape of the fluid which fills the apparatus.

45 This advantage allows the reduction of length and consequently the easy transport of the support, and does not necessitate the introduction of a fresh quantity of compressed fluid in the support when the support is to be erected over again after the reentrance of the tubes in one another. It simply suffices to leave at this moment the said support to develop by itself.

3. When the support is provided with 55 post-wires, stays or ropes, held stretched by the erection of this support and it is subjected to undue lateral strains, for instance— by a gust of wind, these strains produce a hypertension of the post-wires, stays or ropes 60 and a vertical pressure tending to compress the support. This latter stress determines frequently in the other supports the breaking of the parts.

In the new support, when the preceding 65 action is produced, the tubes enter in one an-

other, thus increasing the inner pressure and consequently the rigidity and at the same time the wind has less hold on the support by the fact that it inclines and is shortened.

When the length of these wires, stays or 70 ropes vary by reason of the thermic and hygrometric variations of the atmosphere the tubes follow automatically these movements by reason of their elastic connection. By means of this device the risks of ruptures of 75 the post-supports and posts which are frequently produced by these atmospheric influences are avoided.

When the post has been erected and the support suitably developed, the wires and 80 ropes forming the stays, notwithstanding the atmospheric variations, will with certainty remain constantly stretched in a manner which can be determined beforehand.

4. The present support possesses this advantage that it can be erected at any height and yet preserve its longitudinal elasticity the advantages of which are indicated above.

This ability allows in particular of mounting in advantageous conditions a post the 90 size and shape of which can vary to infinity, it will thus be possible to mount for wireless telegraphy or telephony posts for sending waves the length of which may be varied at will. 95

Claim:

In a telescopic mast, a plurality of tubes capable of sliding in each other, the upper tube being closed at its upper end and the lower tube being closed at its lower end, 100 means held in the lower ends of the inner tubes and engaging the outer tubes and forming fluid tight joints between the tubes in all positions of the said tubes relative to each other, means connected with the lower 105 tube adjacent its lower end for admitting compressed air to the interior of the mast to extend the same, stays secured to the closed top of the upper tube and adapted to cause the tubes to reenter one another slightly 110 when the mast is inclined, the lower tube having a flat outer surface at its closed lower end to rest on the ground, and a conical point at said end adapted to enter the ground to permit the mast to incline under wind pressure, short tube sections arranged 115 loosely between the tubes, rings secured on the lower ends of the tubes surrounded by said tube sections, and on which the lower ends of said tube sections rest, the outer diameter of said rings being less than the inner diameter of the outer tubes to permit an 120 easy sliding movement, and collars screwing on the upper ends of the tubes surrounding the tube sections, the said collars having inwardly extending ledges arranged to permit of slight play between the inner tubes and said ledges, the ledges being adapted to be engaged by the upper ends of said tube sections when the mast is extended to limit the 125 130

upward movement of the tubes relative to each other, the said tube sections serving to maintain the tubes within each other a sufficient distance to insure the rigidity of the 5 mast.

The foregoing specification of my telescopic post-support for sending or receiving

electromagnetic actions, signed by me this 26th day of September 1911.

MARCEL GUICHARD.
